DIAPER

Emily M. Elofson, Indianapolis, Ind.

Application November 10, 1941, Serial No. 418,503

8 Claims. (Cl. 128—284)

This invention relates to diapers, and has for its general object improvements therein, especially improvements which are advantageous with respect to the manner of applying the diapers and which make for neatness of appearance and excellence of fit, in the diapers as worn.

While a diaper is a relatively simple garment, the nature of its use imposes on it certain requirements. It must be capable of being applied in an easy and simple manner. It must be capable of variation in size to suit it during the period of its use to relatively large changes in the size of the child which wears it. In meeting these two requirements, it must also be comfortable and must desirably be of neat appearance. It must be absorbent, and its application must dispose ample thicknesses of material in those locations where greatest absorbency is required and must at the same time avoid bulkiness. Moreover, it must be easily washable, and is desirably of such nature that it dries quickly.

One diaper which meets these conditions to a substantial extent and is in quite common use, is a rectangular piece of cloth approximately 21 inches by 40 inches, and formed of two thicknesses of thin material interwoven at its edges to form marginal areas of a single but heavier thickness. By reason of its thinness, such diaper washes easily and dries quickly, and its shape lends itself to various folds. It is commonly folded lengthwise, on transverse fold-lines, to form a panel whose length is equal to the original width of the piece of material, and whose width is from a third to a fifth the original length of the piece of material. When so folded, the diaper is applied with its original width dimension extending lengthwise of the child's body. This folding necessarily changes during the course of use, to suit the change in size of its wearer. Since this folding must produce a dimension of approximately half the waist measurement of the child, the folding is somewhat critical, and it can not be changed as it is being put on the child. Thus, it inevitably requires considerable guesswork in its folding, even though in some cases it is marked to indicate convenient fold-lines, and it often results in a garment which is neither comfortable nor neat.

Moreover, this and most other diapers are fastened in place with pins, the one just referred to usually being fastened with four pins. The use of pins involves an element of danger, in the possibility of sticking the child and in the possibility of the child's obtaining possession of a pin and putting it in its mouth.

It is the object of my invention to produce a diaper which has the advantages of easy washing and quick drying, which can be applied without the use of pins, which will have a good fit and a neat appearance and may be applied in an easy and simple manner, and which will be inexpensive to manufacture. I accomplish these objects by using a rectangular piece of cloth such as that referred to above, and by supplying that piece of cloth with certain supplemental portions by which it can be easily and simply tied in place to produce a neat-appearing and well-fitting garment.

The accompanying drawing illustrates my invention. In such drawing, Fig. 1 is a diagrammatic view showing how the supplemental portions are desirably cut; Fig. 2 is a view showing the relative positions of the several pieces of a diaper embodying my invention, before they are actually sewed together; Fig. 3 is a view similar to Fig. 2, but with pieces sewed together; Fig. 4 is a diagrammatic view showing the diaper as a garment in the form it takes when applied to a child; and Figs. 5 and 6 are sections showing two of the possible ways in which the diaper may be folded.

The diaper shown in the drawings has as its main body a rectangular piece of cloth CDEF, approximately 21 inches by 40 inches. Desirably, this rectangular piece of cloth is of the same type as the diaper above referred to as in common use, and has a double-thickness central portion with common single-thickness edges. Indeed, it may conveniently be one of such diapers. It is suitably folded, as on its longitudinal center line, to form a panel 10 approximately 10½ inches wide and 40 inches long. To each side edge 11 and 12 of this panel there is secured, as by sewing, a supplemental portion 13. Each supplemental portion 13 is generally in the form of a figure 7, with a horizontal arm 14 and a diagonal arm 15 which makes an angle with the horizontal arm of the order of 60°. The horizontal arm 14 is a waistband tie. Desirably, it is approximately an inch wide at its free end and gradually increases in width toward its base, so that it forms a tie of substantial body which can be washed without tangling and can be easily tied and untied. The diagonal arm 15 is a leg band. It is quite wide at its base and tapers to a width of approximately one inch at its free end. It is joined to the horizontal leg or waistband tie 14 for a considerable distance along that waistband tie. It is secured to the edge 11 or 12 of the panel 10 over a similar

considerable distance from the upper corner of the panel 10.

Desirably, the supplemental portions 13 are formed of integral pieces of cloth, and may desirably be cut from the same material as the panel 10, and from pieces the same size as that panel 10. This cutting is shown in Fig. 1, in which two of the pieces 13 are laid out on a rectangle one-quarter the size of the piece of material which constitutes the panel 10. Thus, the material for the diapers may be formed in their weaving to pieces suitable for the panel 10, and the portions 13 can be cut from extra ones of those same pieces. It is to be noted that the portions 13 interfit so that in their cutting there is a minimum of waste.

However the portions 13 are made, it is desirable that the waistband ties 14 be straight-cut, so that they extend in the direction of the threads of the material, and that the leg bands 15 be bias cut. This gives a desirable firmness to the waistband and permits the leg band to be yieldable.

Those edges 16 of the portions 13 which are to be sewed to the panel 10 are desirably cut to form a shallow V, for this tends to avoid concentrating the pull of the waistband at the extreme upper edge thereof, and spreads that pull over a considerable area in the portions 13 and in the panel 10.

In addition to the waistband tie 14 and the leg band 15, the portion 13 has a short extension 17 adjacent the edge 16. This extension 17 serves as a reinforcement, for it carries the seam by which the pieces are joined past the lower edge of the leg band 15 to avoid concentrating strain at the end of the seam.

In addition to the portions 13 there are ties 18 secured to the panel 10, desirably by the same seam which secures the portions 13, and located just above the extensions 17 of the portions 13. It is thus apparent that the several pieces of the diaper may be assembled with but two seams, although it is of course necessary to do some additional sewing in order to bind or hem the edges of the portions 13 and the ties 18.

While the preferred form of my diaper has a two-layer panel 10 folded from the double size rectangular piece of cloth CDEF, the panel 10 may be of a single layer. In the preferred form shown in Fig. 2, the edge 12 of the panel 10 is a folded edge, while the edge 11 of the panel 10 is formed by the two overlying edges of the original piece of material. In sewing a portion 13 and a tie 18 to this double-layer edge 11 of the panel 10, the seam is made with only one of the two layers of the panel 10, so that the panel 10 may be unfolded to a single layer, to give the desirable thinness of material for easy washing and quick drying.

In preparing the diaper as shown in Fig. 3 for use, the double-layer panel 10 is folded lengthwise to a length suitable for the child who is to wear it. For a small child, this folding may be on two fold lines—first on fold line A—A and then on the fold line B—B, so that in section the panel appears as shown in Fig. 5. This gives an outer double layer 20 extending from the waistband edge 21 to the fold line B—B; an inner double layer 22 extending from the fold line B—B to the fold line A—A, and which may be slightly shorter than the layer 20; and an intermediate double layer which extends from the fold line A—A to the free edge 23. This intermediate layer will cover an area where added thickness is desirable,

although it is not co-extensive with the other two layers. For a large child, a single fold may be made, with the fold line approximately half way between the ends 21 and 23 of the panel 10. Variations of these folding arrangements will of course be obvious, for the length of the diaper in its folded position as shown in Figs. 5 and 6 should be such that when it is put on a child, the lower fold, as B—B in Fig. 5, may be brought upwardly between the legs of the child and will lie at the waist of the child. But this length is not especially critical, as will be explained.

If desired, a layer of rubberized material may be inserted inside the outermost layer of the diaper, as between the two layers of the outer double layer 20 and coextensive with that outer layer 20.

With the panel 10 folded as in Figs. 5 and 6 the diaper may be put on a child to form a garment like that illustrated (somewhat diagrammatically) in Fig. 4. In this garment, and referring to both Figs. 4 and 5, the upper edge 21 of the panel 10 lies at the extreme rear. Immediately inside this edge 21 lies the folded edge A—A. At the front of the garment at the waistline lies the fold edge B—B. The supplemental portions 13 secured at the edges of the outer layer 21 extend around the sides to overlie the material adjacent to the fold edge B—B, and the waistband ties 14 are tied together. Desirably, the fold B—B, at least over its center portion, extends somewhat above the waistband ties 14. The leg bands 15 extend inwardly and downwardly, and around the legs in the opposite direction from the layer 20 of the panel, to a point adjacent the ties 18, to which the ends of the leg bands 15 are tied. This tying is done at the sides of the garment and of the child, in readily accessible locations where the tyings are in little danger of becoming wet. The edges of the layers 20—22 extend slightly beyond the leg bands 15, so that those edges are held by the leg bands in proper position.

Because the diaper is held on by the ties 14 and by the leg bands 15, the width of the panel 10 need not be changed as the child grows larger, and there is no necessity for having the width of that panel of any particular dimension so that it will form a proper waistband. As a result, the width of the panel is not critical, and the unchangeable width shown can be satisfactorily used. Moreover, the length of the panel after its folding is not overly critical, for the amount of material at the front edge B—B of that folded panel which extends beyond the ties 14 may vary considerably without loss of neatness or comfort. In addition, it is entirely convenient and possible to change the length of the folded panel during the process of putting the diaper on a child.

The diaper is easily applied and simple to use, and requires no guesswork folding. It is secured in place with but three tyings, all of which are readily accessible without turning the child. The resulting garment is firmly held in place and is of neat appearance.

I claim as my invention:

1. A diaper, comprising a relatively long narrow panel of a plurality of thicknesses of material folded from a rectangular body and capable of being unfolded, supplemental portions joined to the side edges of said panel at one end thereof, each of said supplemental portions comprising a waist-band tie and a leg-band extending diagonally downward from the juncture of said tie with said panel, said leg-band being of sub-

stantial width at its base, tapered toward its free end, and joined to both said tie and the side edge of said panel over a considerable distance from the corner of said panel, a side tie for said leg band adjacent the panel-side of the base thereof, said panel being adapted to be folded lengthwise to suit the intended wearer.

2. A diaper, comprising a relatively long narrow panel, supplemental portions joined to the side edges of said panel at one end thereof, each of said supplemental portions comprising a waist-band tie and a leg-band extending diagonally downward from the juncture of said tie with said panel, said leg-band being of substantial width at its base, tapered toward its free end, and joined to both said tie and the side edge of said panel over a considerable distance from the corner of said panel, a side tie for said leg band adjacent the panel-side of the base thereof, said panel being adapted to be folded lengthwise to suit the intended wearer.

3. A diaper as defined in claim 2, in which each supplemental portion is an integral piece of material.

4. A diaper as defined in claim 2, in which each supplemental portion is an integral piece of material and said waist-band ties are straight-cut and said leg-bands are bias-cut.

5. A diaper as defined in claim 2, in which the edge of each supplemental portion which is sewed to the panel is cut to form a shallow V so that the pull on said waist-tie reacts on said panel over an area of considerable width.

6. A diaper as defined in claim 1, in which the panel is formed by folding the rectangular body

on its longitudinal center line, one supplemental portion is joined to said panel at said center line, and the other supplemental portion is joined to one edge of said rectangular body, to leave said body free to be unfolded.

7. A diaper, comprising a panel of a plurality of thicknesses of material adapted to be applied to a child with its upper end at the back of the child's waist and its other end at the front of the child's waist, waist-ties to extend from the edges of said upper end around the child's waist and over the said panel other-end and to be secured together at the child's waist-front, leg bands secured to said panel upper-end and said waist-ties to extend from front to rear between the child's legs and there-around, and means at the sides of the diaper for securing the free ends of the leg bands, whereby said leg bands hold intermediate portions of said panel against the legs of the child.

8. A diaper comprising a rectangular panel adapted to be applied to a child with its upper end at the back of the child's waist and its other end at the front of the child's waist, waist-band forming means secured to the edges of said upper end and overlying said other end of the panel, leg bands secured to the edges of said upper end and to said waist-band means to extend inward and from front to rear between the child's legs and there-around, and means for fastening the ends of said leg-bands at the sides of the diaper, whereby said leg bands hold intermediate portions of the panel close around the legs of the child.
